PNEUMATIC HAND FORMER

Roger S. Raymond, Redondo Beach, Calif., assignor to North American Aviation, Inc.

Application July 17, 1950, Serial No. 174,279

3 Claims. (Cl. 153—48)

1

The present invention relates to means for performing hand finishing operations on formed sheet metal parts. Formed parts made from sheet material such as the aluminum alloys commonly employed in aircraft construction are frequently made by hydropress operations. While this type of forming provides for rapid production of parts with a minimum amount of tooling, the parts may require certain hand finishing operations in order to obtain the desired detailed contours and dimensional tolerances. In the past it has been common practice to perform these finishing operations by hand as a bench operation by the use of a rawhide mallet. The present invention provides means for accomplishing such finishing operations in an expeditious manner by successively bringing the various portions of the work piece into contact with a power driven head. The operator causes to be directed a series of short quick blows to effect close conformity of the finished part to the die or form block.

It is therefore an object of the present invention to provide means for performing finishing operations on sheet metal parts.

It is also an object to provide such means which are rapid and highly effective in operation.

It is a further object of the present invention to provide sheet metal finishing means which are simple to operate, inexpensive to construct and which are readily adaptable to the finishing operations of a great variety of shapes and contours.

Other objects of invention will become apparent from the following description taken in connection with the accompanying drawings, in which

Fig. 1 is a top plan view of the subject sheet metal forming equipment,

Fig. 2 is a front elevational view,

Fig. 3 is a section taken at the line 3—3 of Fig. 4, and

Fig. 4 is a longitudinal sectional view taken on the line 4—4 of Fig. 1.

Referring to the drawings, the unit comprises a percussion type pneumatic motor 1 driven by compressed air, the rate and amplitude of the stroke of which may be varied by the pressure of the air admitted thereto. The motor unit is positioned upon a work surface 2 by means of yokes 3—4 secured to the work surface by pairs of bolts 5—5 and 6—6. The yokes are arranged to engage the body of the motor 1 and are provided with lugs 7—7 and 8—8 through

which the bolts pass. The yokes are also provided with upwardly extending tabs 9 and 10 interconnected by a longitudinal plate 11. The motor is resiliently mounted by means of compression type coil springs 12 provided about the shanks of the hold down bolts 5 and 6, bearing against washers 13 at the under surfaces of the bolt heads and upon the upper surfaces 14 of the lugs 7—8 of the yokes 3 and 4. Spacers 15 are provided beneath the lugs 8 for supporting the rear yoke 4 to position the unit with respect to the surface 2, the front yoke 3 being carried upon adjustable means to be hereinafter more fully described.

15 The forward portion of the motor 1 is provided with a percussive head 20 which is positioned between a pair of guiding elements 21—22 formed of short angle sections placed back to back. The percussive head 20 is accordingly guided for limited fore and aft movement and is restrained from side movement. Small tabs 23—24 are also provided to prevent the percussive head from becoming displaced upwardly beyond a certain limited amount. A work engaging 20 face piece 25 is provided on the percussive head. The face piece may be made of any suitable durable and non-abrasive material and a form of impregnated fiberboard known to the trade as "red fiber" may be very satisfactorily employed.

25 Referring now to Fig. 4 the work piece may be seen indicated in phantom at 30 in position upon the die block 31. The motor 1 is arranged to be actuated by means of an air control valve 32 which controls the admission of compressed air through the line 33 into the cylinder of the motor 1. Automatic actuation of the unit is provided when the work piece 30 is brought in contact with the face piece 25. This is accomplished by the following arrangement wherein a control rod 34 is supported and journaled for limited sliding movement in the pair of upstanding tabs 9—10 attached respectively to the forward and rear yokes 3—4. The forward portion of the rod 34 carries a depending plate 37 which engages the spherical-ended connecting link 38 between the forward portion 39 of the motor and the percussive head 20. The rear end of the rod 34 terminates in a flattened head 35 which bears upon an arm 36 of a bell crank 41 pivotally mounted at 42 between a pair of plate members 43, the opposite arm 44 bearing upon the motor air control valve 32. Pressure of the work piece 30 against the face piece 25 is transmitted through elements 20—38—37 to the

rod 34 which in turn actuates the control valve 32 through the action of the bell crank 41. Integral with the rod 34 is an annular shoulder 45 against which compression spring 46 bears, the other end of the spring being seated against plate 10. The work piece pressure must overcome the spring to actuate the control valve 32 and the spring 45 returns the control linkage upon relaxing the work piece pressure, releasing the control valve 32, which is also spring loaded to the closed position. Adjustment means on the rod 34 for control of the actuation of the air valve 32 is provided by means of a threaded portion 47 which engages a fitting 48 integral with the plate 37. A lock nut 49 bears against the forward face of the plate 37 to secure the rod 34 in adjusted position.

To accommodate angles other than 90° on flanged portions of the work pieces the entire motor and its associated mechanism may be tilted with respect to the work surface. This is accomplished by means of a hand control 50 having a shaft 51 which is threaded at 52 for engagement with a corresponding threaded vertical bore in the work surface 2. Below the work surface the shaft 51 has an extension 53 which bears at 54 against the upper surface of one end of a pivoted lever 55. The lever is pivoted at 56 upon a pair of brackets 57 which depend from the lower face of the work surface. The forward end of the lever 55 bears at 58 against the under surface of the forward yoke 3. When the shaft extension 53 is moved downwardly the forward end of the motor unit is raised accordingly. This movement is effected against the tension of the springs 12 which bear upon the lugs 7 of the forward yoke 3. The lugs of the yokes 3 and 4 are provided with slightly enlarged openings at 59 through which the bolts 5 and 6 pass and accordingly the yokes may be tilted sufficiently to accommodate the desired angular adjustment. Raising the forward end of the motor tends to vary the angular relationship of the front face of the member 25 with respect to the work surface 2. Where angular adjustment in excess of that obtainable is required the face of the element 25 may be beveled or appropriately contoured.

Although the invention has been described and illustrated in detail, it is to be clearly understood that the same is by way of illustration and example only and is not to be taken by way of limitation, the spirit and scope of this inven-

tion being limited only by the terms of the appended claims.

I claim:

1. A device for finishing sheet material on a die comprising a work supporting member adapted to support said die; a pneumatic percussion type motor carried by said member; a percussive head carried by said motor for reciprocal movement in a path fixed relative thereto upon actuation of said motor; a source of pressurized air connected with said motor for operation thereof; valve means associated with said motor for normally preventing entrance of said pressurized air into said motor for precluding operation thereof; and mechanical means interconnecting said percussive head and said valve means whereby said valve means is responsive to pressure on said percussive head for allowing entrance of said pressurized air into said motor for permitting operation thereof.

2. A device as recited in claim 1 including in addition means for varying the angle of said motor relative to said work supporting member whereby said path of said percussive head is varied.

3. Apparatus for finishing sheet material comprising a percussion type pneumatic motor, a percussive head driven by said motor in a path defined thereby; a pair of yokes secured to said motor; a support member; spring means urging said yokes toward said support member; and means adapted to pivot said motor with respect to said support in opposition to said spring means whereby said path of said percussive head is adjusted.
